Patented Oct. 23, 1917.

UNITED STATES PATENT OFFICE.

JAMES K. LANNING, OF FALL RIVER, MASSACHUSETTS.

PICKER-CHECK.

1,244,101.

Specification of Letters Patent. Patented Oct. 23, 1917.

Application filed November 26, 1915. Serial No. 63,384.

To all whom it may concern:

Be it known that I, JAMES K. LANNING, a citizen of the United States, and a resident of Fall River, in the county of Bristol and 5 State of Massachusetts, have invented an Improvement in Picker-Checks, of which the following description, in connection with the accompanying drawings, is a specification, like characters on the drawings representing like parts.

This invention relates to picker checks. In order that the principle of the invention may be readily understood, I have disclosed a single embodiment thereof in the accompanying drawing, wherein—

Fig. 1 is a front elevation of a loom having my invention applied thereto;

Fig. 2 is an underneath plan view of a portion of the raceway of the loom and representing my invention as applied thereto;

Fig. 3 is a similar view of a modified form of my invention;

Fig. 4 is a side elevation of the construction shown in Fig. 3; and

Fig. 5 is an underneath plan view of still another form of my invention.

An important object of my invention is to provide a picker stick check constructed and arranged to hold the picker stick accurately in its outward position in contact with the point of the shuttle, so that upon the inward throw of the picker stick, the shuttle is at once thrown by the picker stick without lost motion. Other objects of the 35 invention will be set forth more fully hereinafter.

My improved picker check may be applied to any type of loom having picker sticks. I have herein shown a conventional 40 loom having a frame 1, a race 2 and picker sticks 3. The picker sticks may be rocked in any suitable manner, and to that end are herein represented as provided with shoes 4. The parts thus far shown may be of any 45 desired or usual construction.

In that form of my invention shown in Figs. 1 and 2, I attach preferably to the under side of the race 2 of the loom, as by pivotal bolt 4^a a picker stick check herein 50 shown as consisting of a member 5 having integral therewith arms 6—6 extending in general parallelism with the slot 7 in the race. The arms 6—6 are slightly inclined toward each other in the direction of outward movement of the picker stick at that

side of the loom, so that as the picker stick moves outwardly, it is brought to rest at a predetermined position, as indicated in Fig. 1.

The check consisting of the member 5 with its arms 6—6 may be formed of one or more pieces and may be of any suitable material. Preferably, however, it is formed of some hard wood, such, for example, as maple, and the arms 6—6 are very slightly resilient, so that they yield outwardly somewhat in the outward movement of the picker stick at that side of the loom. I am aware that it has heretofore been proposed to provide a picker or shuttle check made of general U-shaped form and of one or more pieces of metal, the wings thereof being resilient to a considerable extent, as shown, for example, in the patent to Ayer, No. 872,779, December 3, 1907. In such constructions, however, the wings of such picker or shuttle checks are, however, substantially highly resilient, and the construction and mounting of the check are relatively complicated and expensive.

An important purpose of my invention is to provide a picker check of exceedingly simple construction, which may be readily applied to the under side or to the top side of the race of the lay without altering the construction of the loom and at very slight cost.

A picker stick in normal operation has slight lateral play, frequently about one quarter of an inch. By pivoting the picker check, as at 4^a, the check is permitted to yield sufficiently to accommodate such motion. Preferably also I provide lateral stops 4^b secured to the race of the lay and herein shown as having adjusting screws 4^c to limit the pivotal movement of the picker 95 check.

In Figs. 3 and 4, I have shown another form of my invention. Therein I have substantially reversed the construction shown in Figs. 1 and 2 and have provided a picker stick check composed of a member 8 which is secured by pivotal bolt 9 to the outer end of the raceway of the loom or to an extension thereon. I have herein represented the race as having secured to its under side 105 at its outer end a forked extension 10 to which the said check 8 is secured by the pivotal bolt 9 so as to lie in general parallelism therewith and preferably at the upper side thereof, as shown most clearly in 110

Fig. 4. The said picker stick check is provided with arms 11—11, preferably but not necessarily integral with the member 8 and slightly resilient. The said check may be 5 formed of any suitable material, but preferably is formed of wood. I have herein represented the inner ends of the arms 11 as slightly beveled or flaring at the points 12, 13. The arms 11—11 very slightly approach 10 each other in the direction of inward movement of the picker stick 3.

In this form of my invention I have represented means for limiting the pivotal movement of the check, the same here consisting 15 of a transverse slot 13^a which receives a pin 13^b upon the bracket 10.

In Fig. 5, I have shown still another form 20 of my invention. Therein, instead of providing a picker check formed of a single piece of material, I provide two members 14, 15 secured by pivotal bolts 16, 17 to the under side or to the upper side of the race of the loom, as for example, in the manner shown in Fig. 1. The said members 14, 15 25 have extensions or arms 18, 19 similar in construction and function to the arms 6—6 shown in Fig. 2, and hence needing no further description. I preferably provide limiting means, here consisting of stops 20 provided with adjusting screws 21. If desired, 30 I may connect the arms 18, 19 by a yoke or in other suitable manner to compel unison movement.

It will be evident from the foregoing description 35 that the picker stick check is of exceedingly simple construction and inexpensive. It may be applied to substantially any type of loom without substantial alteration thereof, and in practice effectively 40 checks or holds the picker stick at a predetermined point, thus insuring contact of the picker stick and shuttle at the limit of outward throw of the shuttle.

Having thus described one illustrative 45 embodiment of my invention, I desire it to be understood that although specific terms are employed, they are used in a generic and descriptive sense and not for purposes of limitation, the scope of the invention being 50 set forth in the following claims.

Claims:

1. In a loom, a lay, a picker stick, and a

frictionally acting picker check therefor consisting of slightly resilient members extending in substantial parallelism with the 55 walls of the picker stick slot and rigidly connected together, and conjointly laterally movable to accommodate themselves to the movement of the stick.

2. In a loom, a lay, a picker stick and a 60 frictionally acting picker check therefor, consisting of means pivoted to a face of the lay and having slightly resilient arms extending in substantial parallelism with the walls of the picker stick slot, said arms 65 being rigidly connected together and conjointly movable in the same direction to accommodate themselves to the movement in either direction of the picker stick.

3. In a loom, a lay, a picker stick and a 70 frictionally acting picker check therefor consisting of two slightly resilient arms having a common pivot and extending in general parallelism with the walls of the picker stick slot, said arms being rigidly 75 connected together and conjointly movable laterally in the same direction to accommodate themselves to the lateral movement of the picker stick.

4. In a loom, a lay, and a picker stick 80 therefor, consisting of a member having a pivot and two longitudinally extending, slightly resilient arms extending in general parallelism to the slot of the picker stick, together with means to limit the lateral 85 movement of the arms in either direction.

5. In a loom, a lay, a picker stick and a 90 frictionally acting picker check therefor, consisting of two slightly resilient arms extending longitudinally of and inwardly overlapping the slot of the picker stick for the greater part of their length, said arms being laterally movable, and means engageable with said longitudinally extending arms relatively remote from the ends of 95 said slot to limit lateral movement thereof.

In testimony whereof, I have signed my name to this specification, in the presence of two subscribing witnesses.

JAMES K. LANNING.

Witnesses:

IRVING U. TOWNSEND,
F. IRENE CHANDLER.
